ELECTRIC SERVICE BOX OR THE LIKE

John R. Geisen, 113 Woodside Place, Fort Thomas, Ky.

Filed May 12, 1961, Ser. No. 65,137

Term of patent 14 years

(Cl. D26—13)

Fig. 1

*FIG. 2**FIG. 3*

FIG. 1 is a perspective view of the front, top and right side of an electric service box, showing my new design.

FIG. 2 is a side elevation thereof as seen from the left of FIG. 1.

FIG. 3 is a bottom elevation thereof.

The characteristic feature of my design resides in the combination on the electric service box disclosed of the particular grooved circular decorations on each of the four sides substantially as shown.

I claim:

The ornamental design for an electric service box or the like, as shown and described.
